WALTER BELLINGHAUSEN AND MARINUS VANDERKLOOT, OF CHICAGO, ILLINOIS,
ASSIGNORS, BY MESNE ASSIGNMENTS, TO INDUSTRIAL PATENTS CORPORATION, OF
CHICAGO, ILLINOIS, A CORPORATION OF DELAWARE

MEAT PRESS

Application filed July 2, 1931. Serial No. 548,339.

The invention appertains to compression apparatus and specifically to a press for reducing meat to compact form and shape for convenience of handling and advantageous 5 marketing.

The invention provides a device of the character aforesaid which is efficient for the purpose stated, substantial in structure, easily operable and capable of withstanding 10 severe strain without becoming disabled.

For a full understanding of the invention and the merits thereof, reference is to be had to the drawing hereto attached and the subjoined description in which corresponding 15 parts are designated in the several views of the drawing and referred to in the specification by like reference characters.

In the drawing:—

Figure 1 is a perspective view of a press 20 illustrative of an embodiment of the invention.

Fig. 2 is a vertical, central, longitudinal, sectional view thereof.

Fig. 3 is a transverse sectional view on the 25 line 3—3 of Fig. 2, looking to the right as designated by the arrows.

Fig. 4 is a perspective view of a slight modification in which an end wall is hinged, as shown in open position.

The pressing or forming chamber comprises a bottom 1, side walls 2 and 3, and 30 end walls 4 and 5. This chamber may be formed in any manner, and in practice it is preferred to construct the same of metal, the bottom 1 and side walls 2 and 3 constituting parts of a single casting. The end walls 4 and 5 are separate and bolted to the side walls. Strengthening ribs 6 brace the side walls and are interposed between the respective 35 walls and extensions of the bottom. In this manner, the chamber is substantial in structure and capable of withstanding severe compressive strain. The side wall 2 projects some distance above the side wall 4 to provide a guide for the plunger and also receives a bracket 7 which is bolted or otherwise secured thereto and in which the compressing screw 8 is mounted.

An abutment is located within an end portion of the pressing or forming chamber 9

and comprises companion plates 10 between which is interposed an expansible helical spring 11. An adjusting screw 12 threaded into the end wall 4 engages the abutment and admits of adjustment thereof to vary the 55 capacity of the chamber. It is observed that the abutment is yieldable by reason of the interposed spring 11, hence, compensates in a measure for a high compressive force, as will be readily appreciated. 60

The plunger 13 is hollow, and in the preferred construction consists of a casting and is of a length and width to fit snugly between the walls of the pressing chamber 9.

The open side of the plunger faces upwardly and is provided with a cap plate 14 to which is fitted a collar 15. Lips 16 project outwardly from the ends of the plunger 13 and are adapted to engage the end walls 4 and 5 and limit the downward movement 70 of the plunger. The compressing screw 8 is mounted in the overhanging portion of the bracket 7 and its lower end engages the collar 15 by means of a swivel joint. Rotation of the screw 8 in one direction lowers the plunger 75 and compresses the material contained in the chamber 9. A reverse rotation of the screw 8 elevates the plunger, thereby admitting of access to the pressing chamber for supplying material thereto or removing the compressed 80 article.

By bolting the end walls to the body of the chamber, either one or both may be readily removed when access to the chamber is desired. In the modification shown in Fig. 4, the end wall 5^a is hinged to the side wall 2, and when closed is made secure by means of turn buttons 17 engaging slots 18 formed in the outer edge portion of the swinging end wall. 90

Meat, foodstuff or other material to be formed into a compact and solid mass is placed in the chamber 9 and is compressed by advancing the plunger 13. The length of the block or compressed body may be varied by 95 adjusting the abutment, and by substituting abutments of different heights the size of the compressed body may be varied, as will be readily comprehended. By forming the bottom 1 and sides 2 and 3 en bloc, joints are 100

obviated and the side walls may be substantially braced to withstand the pressure that may be exerted to reduce the meat or other product to compact form.

5 What is claimed is:

A press comprising a forming chamber and a cooperating plunger, a yieldable abutment within an end portion of the forming chamber, an adjusting screw threaded into an end 10 wall of the forming chamber, a plate connected to the inner end of said adjusting screw and movable by said screw, yieldable means between said plate and said abutment, an end wall hinged to form a swinging end 15 wall and means to lock said swinging end wall in closed position.

Signed at Chicago, in the county of Cook and State of Illinois, this 24th day of June, 1931.

20 WALTER BELLINGHAUSEN.
MARINUS VANDERKLOOT.
